UNITED STATES PATENT OFFICE.

HENRY B. OATLEY, OF FLUSHING, NEW YORK, ASSIGNOR TO THE SUPERHEATER COMPANY, OF NEW YORK, N. Y.

LOCOMOTIVE FRONT END.

Application filed October 19, 1925. Serial No. 63,565.

This invention relates to locomotives and has for its purpose the provision of an improved arrangement for the smokebox or front end.

- 6 The improvement is illustrated in the accompanying drawings. In these Fig. 1 is a central longitudinal section of the front end of a locomotive according to my improved arrangement. Fig. 2 is a section on 10 line 2—2 of Fig. 1. Fig. 3 is a half section on line 3—3 of Fig. 1. Fig. 4 is a fragmentary view on line 4—4 of Fig. 1; Fig. 5 is a view similar to Fig. 1 of a modification; Fig. 6 is a front view of this modification with a portion shown as a section on 15 line 6—6 of Fig. 5.

I shall first describe the form of my invention shown in Figs. 1 to 4. The locomotive in connection with which I describe my 20 invention in these figures for illustrative purposes is one of a standard type equipped with the usual superheater. The barrel of the locomotive is indicated at 1, the steam dome being designated by the reference number 2. From the front flue sheet 3 extend 25 backward the flues 4. Within these flues are located the tubular superheater elements 5 which have their ends connected to the header 6.

30 All of this is of a usual well known construction.

The smokebox sheet 7 which in the ordinary arrangement is a cylindrical sheet is in my construction cut away at the front upper portion so that there are two straight upper edges 8—8 and an arc-shaped edge 9. A flat sheet 10 extends between the edges 8—8, and from its rear end 11 a segment shaped vertical plate 12 extends up to the arc-shaped edge 9. The front end of the smokebox is closed by the sheet 13. The horizontal plate 10 is approximately on a line with the superheater header 6.

A smoke stack 14 extends through the 45 horizontal sheet 10 and is supported on and secured to it by means of the flange 15. The usual petticoat pipe 17 and exhaust base 18 create the draft to send the gases from flues 4 out through the stack.

50 Mounted also above the flat sheet 10 is the throttle 19. This throttle is connected to the superheater header by means of the pipe 20 which is preferably integral with the throttle. The connection between the superheater outlet 21 and the pipe 20 is effected

by means of the flanges 22 and 23, which, it will be observed, lie forward of the vertical sheet 12. The throttle 19 has a readily removable cover 19^a to make the interior of the casing accessible for grinding the valve 60 and for other repairs. The pipe 20 is provided with a connection 20^a by means of which superheated steam can be taken off for auxiliaries.

Steam is brought from the steam dome 2 65 to the inlet 24 of the superheater header by means of a pipe 25. The joint 26 between these two lies outside of the smokebox sheet 7. For this purpose the inlet connection 24 extends through an opening 24^a in the 70 smokebox sheet 7. The sheet 24^b, extending from sheet 7 to the flange 24^c, makes an airtight closure for the opening 24^a so that ingress of air to the smokebox or egress of 75 gases from it through this opening is prevented.

27 is a shutoff valve whereby steam can be shut off directly at the steam dome if necessary.

From the throttle 19 extend downward 80 the two steam pipes 28—28. These are shown to lie in depressions 29—29 of the smokebox sheet although this feature is not essential. It will be noted that the joints 30—30 between the steam pipes 28—28 and 85 the throttle 19 lie above the sheet 10.

The superheater elements 5 are secured to the header 6 by means of bolts and nuts. The nuts 31 it will be noted are on the upper side of the header and are readily accessible.

To close in the throttle and protect it from the weather the curved sheet 32 is used. This is preferably split lengthwise at the 95 top as will be apparent from an inspection of Fig. 4 so that it is readily removable. The front sheet 13 is made to extend clear to the top of the front end of the smokebox so as to enclose at this end the space in which the throttle is located.

The sheet 12 is preferably split as at 33 so it can readily be inserted and removed.

The principal advantages of the improved front end arrangement as above described are that all of the large steam pipe joints 105 lie entirely outside of the smokebox; that a flat surface is provided for securing the smoke stack and making a tight joint between its flange and the sheet enclosing the smokebox; that the smokebox volume is re- 110

duced; that the nuts which must be set up to tighten the joint between the superheater elements and the supheater header are more readily accessible; that the throttle is more accessible for repairs and adjustment, and that the main steam pipes are more accessible for application and replacement.

One of the sources of annoyance in locomotive work is the leaky joints in the main steam pipes. This is aggravated when such joints lie inside the smokebox as in that case the draft is interfered with. By the present arrangement all of these joints lie entirely outside of the smokebox so that they are much more readily accessible for tightening and in case a slight leakage should occur the partial vacuum in the smokebox is not interfered with. This is a very decided improvement as will be readily appreciated by those familiar with this art.

The difficulty of making a tight joint between the flange of the locomotive stack and the ordinary curved smokebox shell is well known to railroad men. There is no ready way of machining the flange to a fit and chipping has to be resorted to. This joint has always been a source of petty annoyance. With a flat sheet such as provided with my improved construction the lower side of the flange can be readily machined and it becomes an easy matter to make a tight joint at this point.

By cutting out the upper portions of the smokebox as I do I reduce the total volume of the smokebox contents. This will result in less eddying of the gases and in a somewhat greater uniformity of their velocity through the smokebox.

The tightening of the nuts 31 of the superheater bolts which has been referred to above is easier with this arrangement than it has been heretofore.

The throttle is no less readily accessible than in the ordinary arrangement and can be repaired and reground directly from the outside without the necessity of removing any sheets or covers except the throttle cover itself. Moreover, the entire throttle can be removed and replaced without breaking any air joint.

The principal difference between the modification shown in Figs. 5 and 6, and the form so far described is that in the modified form the smoke box sheet 7 is cut away back substantially to the flue sheet and the sheet 10 extends over the entire distance from the front end of the smoke box to the flue sheet 3, sheet 12 of the form of Figs. 1 to 4 thereby becoming superfluous. In this form of Figs. 5 and 6, the throttle 19 is located behind the stack 14. This results in the steam pipes 28 going more directly to the steam chests than in the first form. There is also illustrated in this modification a feedwater heater 50 which is supplied with exhaust steam

from the main engine by means of the pipe 51. This feed water heater forms no part of the present invention, and need not therefore be described in any detail. Its location on the flat sheet 10, however, is a very convenient one, and is made possible by my improvement.

The flat sheet 10 has a perforation 52 over which is situated the superheater header 6. This header, which is of a well-known and widely used form, has slots through it to accommodate the bolts on which the nuts 31—31 are threaded. In order to close these openings and so to prevent the flow of air into the smokebox and the flow of waste gases outward from the smokebox, the plate 53 is placed on the header below the nuts 31—31.

The end of the plate 10, which lies adjacent to the flue sheet 3, forms an airtight joint at this point by being bolted or riveted to the angle 54.

It will be understood that the two forms of my invention herein described are illustrative only, and that they may be somewhat varied without sacrificing the inventive idea.

What I claim is:

1. In a locomotive, the combination of a circular front flue sheet; a generally cylindrical smokebox sheet extending forward from it and having its forward upper portion cut away leaving two horizontal edges; a flat sheet extending between said edges; and closure means engaging the front edges of the flat sheet and of the smokebox sheet. 100

2. In a locomotive, the combination of a circular front flue sheet; a generally cylindrical smokebox sheet extending forward from it and having its forward upper portion cut away leaving two horizontal edges; 105 a flat sheet extending between said edges; a stack extending through and secured to the flat sheet; and closure means engaging the front edges of the flat sheet and of the smokebox sheet. 110

3. In a locomotive, the combination of a circular front flue sheet; a generally cylindrical smokebox sheet extending forward from it and having its forward upper portion cut away leaving two horizontal edges; 115 a flat sheet extending between said edges; a stack extending through and secured to the flat sheet; closure means engaging the front edges of the flat sheet and of the smokebox sheet; flues extending back from the flue sheet; a superheater header forward from and above the flues; superheater elements secured to the header and extending into the flues; a throttle located above the flat sheet; a pipe connected to the header and carrying steam to it; a connection carrying steam from the header to the throttle; pipe connections carrying steam away from the throttle; the joints of all said connections lying outside of the smokebox. 130

4. In a locomotive, the combination of a circular front flue sheet; a generally cylindrical smokebox sheet extending forward from it, and having its upper portion cut 5 away substantially to the flue sheet leaving two horizontal edges; a flat sheet extending between said edges; closure means engaging the front edges of the flat sheet and of the smokebox sheet; there being an opening 10 in the flat sheet near the flue sheet; and a superheater header closing said opening.

5. In a locomotive the combination of a circular front flue sheet; a smoke box sheet extending forward from it, said smoke box sheet being cylindrical except that its top is 15 flat from the flue sheet to the front end; closure means engaging the front edge of the smoke box sheet, there being an opening in the flat portion of the smoke box sheet near the flue sheet; and a superheater header 20 closing said opening.

HENRY B. OATLEY.
